UNITED STATES PATENT OFFICE.

WILLIAM H. FITZ GERALD, OF HARTFORD, CONNECTICUT.

THERAPEUTIC DEVICE.

1,315,825.

Specification of Letters Patent. Patented Sept. 9, 1919.

Application filed April 30, 1917. Serial No. 165,373.

To all whom it may concern:

Be it known that I, WILLIAM H. FITZ GERALD, a citizen of the United States, and a resident of Hartford, in the county of Hartford and State of Connecticut, have invented a new and Improved Therapeutic Device, of which the following is a specification.

My invention relates to devices that are employed in the treatment of diseases, and an object of my invention, among others is to provide a device that will correct various conditions that tend to promote or irritate disease.

15 One form of device embodying my invention and in the construction and use of which the objects herein set out, as well as others, may be attained, is illustrated in the accompanying drawings, in which:

20 Figure 1 is a view in side elevation of my improved device.

Fig. 2 is a view in cross section through the same.

It has been found that certain beneficial results are obtained by abrading or scoring parts of the human body, and my improved device, illustrated and described herein, has been found extremely useful for such purposes.

30 In the accompanying drawings the numeral 5 indicates the scoring member of my improved device and the numeral 6 indicates the pressure member. The scoring member is preferably made of wire disposed in spiral form and annular in shape, and the pressure member 6 extends through the annular member within its coils, the ends of the pressure member being joined as are also the ends of the scoring member.

35 It will be understood that the pressure member is composed of elastic material, as rubber, that will serve to contract the scoring member and thus produce the binding action required of it.

40 It is intended that this device shall be applied to a member of the human body, as a finger, and the device will be of such size as to bind such member to a certain degree,

the pressure member causing this binding action, and the coils of the scoring member 50 serving to produce grooves and ridges in the member to which the device is applied.

The pressure member will also, to a certain extent, determine the depth of the grooves so made as the flesh forming the 55 ridges between the grooves will come in contact with the scoring or pressure member and the depth to which the coils will sink into the flesh is thus determined.

While it is preferred that a separate pressure member shall comprise a part of the structure, yet it will be possible in some instances to obtain the required binding action by constructing the scoring member so that it alone will have more or less elasticity and 60 serve the required purpose.

In accordance with the provisions of the patent statutes, I have described the principles of operation of my invention, together with the device which I now consider 70 to represent the best embodiment thereof; but I desire to have it understood that the device shown is only illustrative, and that the invention can be carried out by other means.

I claim:

1. A therapeutic device comprising an elastic member disposed in annular form, and a series of ribs extending along the surface of said elastic member and disposed to 80 form a scoring element.

2. A therapeutic device comprising a scoring member, having an opening extending lengthwise thereof and having ribs for scoring purposes, and a binding member 85 located within and inclosed by said scoring member to impart elasticity to said scoring member.

3. A therapeutic device comprising a scoring member made from wire spirally 90 arranged and annularly formed, and an elastic core extending and inclosed within the spirals of said binding member to impart elastic action thereto.

WILLIAM H. FITZ GERALD.
